UNITED STATES PATENT OFFICE.

ALFRED HORATIO HUMPHREY, OF SALEM, NEW YORK.

LICENSE-PLATE UNIT.

Application filed December 8, 1925. Serial No. 74,105.

My invention relates to license plates, particularly to a hinged license plate mounted on a casing adapted, in practice, to be illuminated for increasing the visibility of the 5 perforated characters, letters and numbers of the license plate.

The general object of my invention is to provide a hinged license plate characterized by an inseparable connection between the 10 hinge elements and of such a character as to require the plate to be mutilated or destroyed in order to be removed.

The manner and means whereby the above and other objects are attained will clearly 15 appear as the description proceeds.

Reference is to be had to the accompanying drawings forming a part of this specification, it being understood that the drawings are merely illustrative of one example 20 of the invention.

Figure 1 is a transverse longitudinal section through the license plate embodying my invention, the section being taken on the line 1—1, Figure 2;

25 Figure 2 is a face view of said license plate unit;

Figure 3 is a transverse vertical section as indicated by the line 3—3, Figure 2;

30 Figure 4 is a detail in horizontal section on an enlarged scale as indicated by the line 4—4, Figure 2;

Figure 5 is a detail in section in the plane of the hinge showing the hinge open, that is, the license plate swung to an open position.

35 In carrying out my invention in accordance with the illustrated example, a casing 10 is provided, here shown as flaring and adapted to receive at the back thereof a single lamp 11 or equivalent light-producing 40 means to illuminate the face plate 12. Said face plate has perforated characters 13 appearing illuminated by the light at the back thereof passing through the perforations.

45 At the back of the face plate 12 is a sheet of transpicuous material 14 usually of celluloid and held in place in any suitable manner as by clips 15.

In accordance with my invention, I provide 50 means to hingedly and inseparably secure the face plate 12 to the casing 10. In the illustrated example one hinge butt 16 is welded or otherwise permanently fastened to the casing 10 at a side edge thereof and said hinge butt is formed with knuckles 17. A 55 second hinge butt 18 is secured by a bolt 19

to the face plate 12 in a manner hereinafter described and has a hinge knuckle 20. A hinge pin 21 passes through the knuckles 17, 20 and completes the hinge.

60 Means are provided at the ends of the pin to prevent removal or any axial movement thereof. An elongated pin-retaining element 22 is welded to the casing 10 and one end thereof 23 overlies the hinge pin 21 and has a concave depression 24 to receive the corresponding end of the hinge pin. A hardened pin-retaining element 22 is provided at each end of the pin 21 and welded to the casing 10. Thus, there can be no separation of the license plate by removal of the hinge pin 21.

70 The bolt 19 that secures the one hinge butt to the face plate 12 is passed through a bolt hole 25 in plate 12 near the hinge end and the material of said plate is then turned 75 back and caused to cover the head of the bolt as at 26, the terminal edge portion 27 of the turned-over portion 26 being welded to the face of the plate. The head of the bolt is therefore made inaccessible from the front of the plate and the turned-over and welded portion 26, 27 must be cut away before the bolt can be reached to be removed as by unauthorized parties.

80 The bolt is made irremovable from the interior of the casing 10 at the back of the plate 12 by means of a nut 28 applied to said bolt 19 after the latter has passed through the hinge butt 18. To lock the nut 28 a screw 90 85 29 is engaged partly with the bolt and partly with the nut 28 and then fastening screw 29 is broken off or cut off flush with the face of the nut and with the end of the bolt so as to be irremovable. All exposed parts of the plate fastener and hinge are hardened.

95 It will be seen that the elements 22 prevent the separation of the hinge by removal of the hinge pin 21 and that the head of the bolt is made inaccessible by the turned-over material of the face plate 12 and finally that the nut 28 is made irremovable by the nut-locking screw 29. Hence, the plate 12 must be destroyed or very materially mutilated 100 or the hinge cut off or removed by a torch before the license plate 12 can be removed for the substitution of another. The letter A indicates an automobile part to which the casing 10 is welded.

105 I have shown a turnable latch element 30 for fastening the free end of the license

plate 12 and it will be understood that said latch is a common expedient and forms no part of the present invention. Also, a border 31 is provided on the casing 10 sur-
5 rounding the license plate 12, but the border may be omitted.

I would state furthermore that while the illustrated example constitutes a practical embodiment of my invention, I do not limit myself strictly to the exact details herein illustrated, since, manifestly, the same can be considerably varied without departure from the spirit of the invention.

Having thus described my invention, I
15 claim:

1. A license plate unit including a casing, members integral respectively with the casing and with said license plate, and irremovable means hingedly uniting said members; together with means additional to said integral members to prevent separation of the license plate from the casing at the hinge.
20 2. A license plate unit including a license

plate, supporting means for said plate, a hinge having a member inseparably held to said supporting means, a second member on said hinge and swingable relatively to said first member, and a bolt uniting said second hinge member to the license plate, a portion 25 of said license plate being turned over the bolt head concealing the same to make said bolt head inaccessible, the turned-over portion being irremovably fastened in position.

3. A license plate unit including a license plate, supporting means for said plate, a hinge having a member inseparably held to said supporting means, a second member on said hinge and swingable relatively to said first member, and a bolt uniting said second hinge member to the license plate, a portion 30 of said license plate being turned over the bolt head concealing the same to make said bolt head inaccessible, the turned-over portion being irremovably fastened in position; 35 together with a nut on the bolt, and means to irremovably lock said nut to the bolt.

ALFRED HORATIO HUMPHREY.
